DATE CALCULATOR

Rene-Louis Revillon, Paris, France, assignor to Totaldator
S.A., Courbevoie, France

Filed June 29, 1970, Ser. No. 23,715

Claims priority, application France Apr. 15, 1970

Term of patent 14 years

Int. Cl. D19—03

U.S. Cl. D74—5

FIG. 1 is a front elevational view of a date calculator showing my new design;

FIG. 2 is a left end elevational view thereof, the opposite end being a mirror image thereof;

FIG. 3 is a top plan view thereof;

FIG. 4 is a bottom view thereof; and

FIG. 5 is a rear elevational view.

I claim:

The ornamental design for a date calculator, as shown and described.
